US00D865725S

(12) **United States Design Patent** (10) **Patent No.:** **US D865,725 S**
(45) **Date of Patent:** **** Nov. 5, 2019**

(54) **ANTENNA**

- (71) Applicant: **SHENZHEN ANTOP TECHNOLOGY LIMITED**, Shenzhen (CN)
- (72) Inventor: **Ruidian Yang**, Shenzhen (CN)
- (73) Assignee: **SHENZHEN ANTOP TECHNOLOGY LIMITED**, Shenzhen (CN)

(**) Term: **15 Years**(21) Appl. No.: **29/681,849**(22) Filed: **Feb. 28, 2019****Related U.S. Application Data**

- (62) Division of application No. 29/604,981, filed on May 22, 2017.
- (51) **LOC (12) Cl.** **14-03**
- (52) **U.S. Cl.** **USPC D14/230**
- (58) **Field of Classification Search**
USPC .... D14/137, 138 R, 138 AA, 148, 155, 167, D14/168, 203.6, 204, 209, 216, 218, 221, D14/230-238, 238.1, 240, 242, 265, 299, D14/343, 358, 509; D10/10 CPC H01Q 7/00; H01Q 13/10; H01Q 9/285; H01Q 19/30; H01Q 19/12; H01Q 1/38; H01Q 1/36; H04B 1/0475; H04B 1/034; H05K 11/00

Primary Examiner — Jeffrey D Asch*Assistant Examiner* — Rebekah A Caruso*(74) Attorney, Agent, or Firm* — Muncy, Geissler, Olds & Lowe, P.C.(57) **CLAIM**

The ornamental design for an antenna, as shown and described.

DESCRIPTION

FIG. 1 is a rear, left perspective view of an antenna showing my new design;

FIG. 2 is a front, right perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a bottom plan view thereof; and,

FIG. 8 is a top plan view thereof.

1 Claim, 8 Drawing Sheets(56)
